DOMESTIC WATER HEATER

Andrew Russo, Fitchburg, Mass.

Application October 31, 1932. Serial No. 640,516

1 Claim. (Cl. 257—235)

This invention relates to a domestic water heater designed to utilize a substantial portion of the heat of the flue gases from a stove or furnace.

- 5 It is the general object of my invention to provide a heater of this type which may be easily and economically constructed and installed, and which will be exceptionally reliable and efficient in operation.
- 10 A further object is to provide a construction by which an unusually rapid transfer of heat from the flue gases to the water is effected.

15 My invention further relates to arrangements and combinations of parts which will be hereinafter described and more particularly pointed out in the appended claim.

A preferred form of the invention is shown in the drawing, in which

20 Fig. 1 is a side elevation of my improved heater assembled in position for use;

Fig. 2 is an end elevation, taken along the line 2—2 in Fig. 1;

Fig. 3 is a sectional side elevation of the heater, and

25 Fig. 4 is a sectional end elevation, taken along the line 4—4 in Fig. 3.

Referring to the drawing, I have shown a flue 10 connected to form a portion of the smoke pipe of a range or furnace or other heating apparatus. My improved water heater also comprises a preferably cylindrical drum or casing 12 having heads 13 and 14 provided with outwardly extending flanges 15 and 16, said flanges closely fitting the flue 10 and forming water-tight joints therewith.

The flanges 15 and 16 are preferably eccentrically located in the heads 13 and 14, so that the flue 10 passes through the lower portion of the casing 12, as clearly shown in Figs. 3 and 4.

40 A water inlet or supply pipe 20 is connected to the heater through the lower portion of the casing 12 and a water outlet or delivery pipe 22 is connected through the upper portion of the casing 12.

45 A heating coil 30 is mounted within the flue 10 and extends longitudinally thereof. The inlet end 31 of the coil is connected around the end of the flue 10 and through the head 13 to the water space of the casing 12 at a point not far removed from the inlet pipe 20. The other end 32 of the coil is connected around the opposite end of the flue 10 and through the head 14 to the water space of the casing 12 near the opposite end of the casing and relatively adjacent to the

In the commercial construction of my invention, the flue 10 is preferably a separate piece of pipe of somewhat heavier construction than ordinary stove pipe and forms a permanent part of the water heater. The flue 10 is of such diameter, however, as to be conveniently connected into the usual stove or furnace pipe S, which may be easily notched and fitted around the coil connections.

I also find it desirable to provide a depending extension 50 of the flue 10 to which the leakage, if any, from the casing 12 to the flue 10 will be conducted. An upwardly swinging door 51 normally closes the extension but permits escape of any substantial accumulation of water.

Having described the details of construction of my improved water heater, the operation and advantages thereof will be readily apparent. A rapid interchange of heat occurs between the flue gases and the water in the coil 30, causing the water to circulate through the coil and to escape at the end 32 thereof, such escaping heated water being replaced by cooler water entering the end 31 which is adjacent the inlet pipe 20.

The heated water naturally rises in the casing 12 and may be drawn off through the outlet pipe 22. While the water in the coil 30 is more rapidly heated, the water in the casing 12 surrounding the flue 10 also takes up a substantial amount of heat and thus increases the rapidity of operation of the heater.

In practical operation it is found that a heater constructed as above described furnishes an ample supply of water heated to as high a temperature as is desirable for domestic purposes.

Having thus described my invention and the advantages thereof, I do not wish to be limited to the details herein disclosed, otherwise than as set forth in the claim, but what I claim is:—

A domestic water heater comprising a substantially cylindrical casing horizontally positioned when in use and having a water inlet at the bottom and adjacent one end of said casing and a water outlet at the top and adjacent the other end of said casing, said casing having also outwardly extending annular flanges eccentrically positioned in the opposite ends of said casing and substantially nearer the bottom edges thereof, a relatively heavy pipe section extending as a single piece through said casing and beyond said flanges, said pipe section closely fitting said flanges and being permanently secured in water-tight relation therein, the ends of said pipe section being adapted to fit within commercial smoke flues, and a heating coil mounted in the

portion of said pipe section within said casing but spaced radially therefrom and having its ends extending along said pipe section and outwardly around the ends of said pipe section and said coil having reversely directed extreme end portions detachably connected through the ends of said casing to the water space therein, one end of said coil being connected to said casing below said

pipe section at the water inlet end and the other end of said coil being connected to said casing above said pipe section at the water outlet end, said casing, pipe section and heating coil constituting a unit when assembled but said heating coil being readily removable from said pipe section. 80
